UNITED STATES PATENT OFFICE

PHILIP SHERMAN RUSSEL, OF DETROIT, MICHIGAN, ASSIGNOR TO DETROIT LUBRICATOR COMPANY, OF DETROIT, MICHIGAN, A CORPORATION OF MICHIGAN

CONTROL MEANS

Application filed December 31, 1930. Serial No. 505,713.

My invention relates to new and useful improvements in pressure control means, and more particularly to a device for regulating or controlling the pressure at which a fluid is delivered.

An object of my invention is to provide a device which will prevent delivery of fluid from a pressure source at a pressure below a predetermined minimum and at a pressure above a predetermined maximum.

Another object is to provide a device having means to adjust the range between minimum and maximum pressures at which fluid will be delivered.

15 Another object is to provide a device having adjustable means to determine the minimum or maximum delivery pressure without varying the range between minimum and maximum delivery pressures.

20 The invention consists in the improved construction and combination of parts, to be more fully described hereinafter and the novelty of which will be particularly pointed out and distinctly claimed.

25 In the accompanying drawing, to be taken as a part of this specification, I have fully and clearly illustrated a preferred embodiment of my invention, in which drawing—

Figure 1 is a vertical central section 30 through the regulating device of my invention, but with certain of the internal elements shown in elevation, and

Fig. 2 is a view in section on the line 2—2 of Fig. 1.

35 Referring to the drawing by characters of reference, 1 designates the hollow casing or body member of my device having an internal chamber 2 with a plurality of inlet ports 3, 4, of which one is normally closed by a plug 40 member 5, or, if desired, a pressure gauge (not shown) may be attached thereto to indicate the pressure within the chamber. Opening from the chamber are a plurality of outlet ports 6, 7, preferably two in number, 45 and positioned in the end and side walls respectively of the casing, the port 7 serving as a by-pass outlet and being preferably substantially in line with the inlet port 3 to facilitate assembly of the parts. The port 6 50 is provided by the longitudinal bore 8 of a

nipple member 9 which is threaded or otherwise secured and sealed in an aperture 10 in the casing end wall. Within the bore 8 is an annular flange 11 forming an inwardly facing valve seat, and through the member 9 55 on the inlet side of the valve seat are ports or passages 12 opening transversely into the bore 8. The outlet port 6 is controlled by a valve member 13 having its stem guided in the bore 8, as at 14, for reciprocation of the 60 valve proper 15 to and from its seat, the valve 15 preferably being substantially conical. The member 13 has a stem extension member 16 having a socket 17 in the upper end thereof, in which the free end of the valve stem 65 seats and is secured, as by a cross-pin 18, the upper end of member 16 extending into the bore 8 which is of enlarged internal diameter, as at 19, to guidingly receive the end of member 16. Intermediate its ends the members 70 16, which is preferably cylindrical, is of reduced cross-section, as at 20, to provide an inward or downward facing annular shoulder or abutment 21 on the valve member 13, and for a purpose to be described. 75

The outlet port 7 is provided by the longitudinal bore 22 of a nipple member 23 which is threaded or otherwise secured in an aperture 24 in the casing side wall. Within the bore 22 is a sleeve or valve seat member 25 which is longitudinally adjustable therein, preferably by threaded engagement with member 23, as at 26. Through member 25 is a longitudinal passage 27 which is constricted by an annular internal flange 28, 80 which provides an inwardly facing shoulder forming a valve seat. Controlling the outlet port 7 is a valve member 29 which cooperates with the valve seat of flange 28, the stem 30 of member 29 preferably being polygonal in cross-section, and is guided for reciprocation by the walls of passage 27. When the device is employed for regulating or controlling liquid pressure, the member 29 is preferably provided with a shallow 85 groove or slot 31 extending across the valve seat so that air or other gas which might trap with the chamber 2 and cause the pump or pressure creating means to lose its prime, 90 will be initially expelled from the chamber. 95 100

Acting on the member 29 and normally tending to move the same from its seat toward open position, is a resilient means 32, preferably a spring member of the coil type which surrounds the stem 30 and the inner end of member 25. The spring member 32, which is under compression, abuts the inner end of nipple member 23, and at its opposite end engages a lateral surrounding flange or head member 33 rigid with the free inner end of stem 30. Engaging and bearing against the member 33 or end of stem 30, is one end of a lever means 34 which is fulcrumed intermediate its ends and pivotally supported on a pin 35 extending therethrough. The pin 35 is threaded or otherwise rigidly secured at one end in a boss 36, or the like, projecting into chamber 2 from the casing wall. Opposing the means 32 is a resilient means 37 which normally exerts a force slightly in excess of the force of spring means 32 so as to hold the valve member 29 closed. The means 37 preferably comprises a coil spring held under compression and which is seated at one end in an axial socket or recess 38 in a plug member 39 threaded or otherwise secured in an aperture 40 through the casing side wall below the aperture 24. The other end of the spring 37 surrounds a supporting finger or guide member 41 carried by the lever means 34 and engages the free end of the lever means 34 on the opposite side of its fulcrum from the valve member 29 acting to turn the same 35 counterclockwise of Fig. 1 about pin 35 to seat the valve member 29. The lever means 34 preferably comprises a substantially vertically extending member 41* which is U-shaped in horizontal cross-section, having substantially parallel, horizontally extending arms 42 which extend laterally adjacent the opposite sides of the valve member 13 at the reduced portion 20 in the path of travel of the shoulder 21 so as to be engaged thereby on movement of the member 13.

The casing 1 has a depending hollow open-ended extension 43, preferably cylindrical and substantially concentric with the port 6, the lower end of the extension being closed and sealed by a means 44 movable in response to fluid pressure in the casing. The means 44 preferably comprises a substantially cylindrical, circumferentially corrugated, resilient, metal member or bellows having its lower end sealed to the inner periphery of a ring member 45 which seats against and is sealed to the underface of an annular flange or shoulder 46 in the extension 43. The means or member 44 has a head or end wall 47 to which the free lower end of the stem extension member 16 is secured, as at 48, so that the valve member 13 is movable with and is operable by the means 44. The member 13 is preferably provided with a

guide means 49 comprising an apertured cross-bar or member through the guide aperture 50 of which the extension member 16 reciprocably extends. Secured on and closing the lower end of the extension 43 is a cap member 51 having a peripheral, internally threaded flange 52 which threadedly engages the lower end portion of extension 43. Opposing movement of the means 44 and member 13 in response to fluid pressure in the casing and normally tending to maintain the member 13 seated, is a resilient means 53, preferably a coil spring positioned within the bellows 44 and having one end engaging the head 47 and being supported at its other end on a spring seat member 54. The spring 53 is held under compression and the expansive force thereof is adjustable by an adjustment member 55, preferably a threaded plunger or screw which is threaded through a central aperture 56 in the cap member 51 in line with member 13 and on the inner end of which the seat member 54 is supported. The outer end of the member 55 which is provided with a screw driver slot 57 may be enclosed by a cover member 58 removably secured to the cap member 51.

The operation of my device is as follows: The device is connected in a delivery line for fluid under pressure, such, for example, as the liquid fuel delivery line of an oil burner, or the like, with the inlet 3 or 4 connected to the discharge side of a pump or other pressure means, with the outlet 6 leading to the burner nozzle and with the outlet 7 connected to a conduit which preferably returns to the source of supply. The member 25 is adjusted preferably on assembly, and then staked or otherwise fixed in adjusted position to determine the clearance between the shoulder 21 and the arms 42, which adjustment determines the differential pressure between the opening of port 6 and the opening of port 7, i. e., determines the increased pressure above the pressure which causes initial opening movement of member 13 which will act through means 44 to move shoulder 21 into engagement with arms 42 to start opening movement of valve member 29. The adjustment screw 55 is then moved in or out to adjust the expansive force of spring 53 to determine the fluid pressure in chamber 2, which acting on bellows head 47 will overcome the force of spring 53 and cause opening movement of valve member 13. Assuming that the screw adjustment 55 has been set for a minimum pressure of—say, fifty pounds—and the clearance between 21 and 42 has been set for a differential pressure of—say, twenty-five pounds—which is independent of and not varied by adjustment of the force of spring 53, then when the pump or other pressure means is started pressure will build up in chamber 2. Any air or gas which has been forced into the chamber 2 by the

pump will be vented through the by-pass slot 31, which is too small to pass any quantity of liquid which would interfere with proper operation of the device. When the pressure in chamber 2 has built up to the desired minimum pressure, the pressure acting on means 44 will move the same and retract member 13 to open port 6. Should the pressure within chamber 2 continue to build up or increase to the desired maximum delivery pressure, then the pressure on means 44 will have moved shoulder 21 into engagement with arms 42 and will have balanced the slightly excess force exerted by spring 37 over that of spring 32, so that any further increase of pressure in chamber 2 will, acting through means 44, move the lever means 34 clockwise of Fig. 1 to cause opening of port 7 by overcoming the opposing resistance of spring 37 to spring 32 and thus permitting the spring 32 to move valve member 29 toward open position. Since the degree of opening movement of valve member 29 and the quantity of fluid bypassed depends upon the pressure within chamber 2 acting on means 44, it is evident that the pressure in the delivery line leading from port 6 cannot increase above a pressure equal to that for which valve member 13 is set to open plus the range between minimum and maximum delivery pressure or the differential pressure which will open port 7.

What I claim and desire to secure by Letters Patent of the United States is:

1. A device of the character described, comprising a hollow casing having an inlet port and a plurality of outlet ports, a valve member controlling each of said outlet ports, one of said valve members being operable upon predetermined fluid pressure in said casing, another of said valve members being operable upon a predetermined increase of fluid pressure in said casing, means normally tending to move said other valve member toward open position, means responsive to fluid pressure in said casing and operatively connected to said one member, means exerting a predetermined resistance to operation of said responsive means, and means opposing said first-named means and operable by said responsive means upon a predetermined increase of fluid pressure in said casing to permit said first-named means to actuate said other valve member.

2. A device of the character described, comprising a hollow casing having an inlet port and a plurality of outlet ports, a valve member controlling each of said outlet ports, means responsive to fluid pressure in said casing and operatively connected to one of said valve members to move said one member to open position, means resisting operation of said responsive means and determining the fluid pressure at which said one valve member will be opened, resilient means operable to open another of said valve members, means

resisting operation of said resilient means and normally maintaining said other valve member closed, said last-named resisting means being operable by said responsive means upon a predetermined increase of fluid pressure to permit operation of said resilient means.

3. A device of the character described, comprising a hollow casing having an inlet port and a plurality of outlet ports, a valve member controlling each of said outlet ports, means movable in response to fluid pressure in said casing on the inlet side of said valve members and operatively connected to one of said valve members to cause opening movement thereof, means resisting opening movement of said one valve member by said responsive means, and means engageable by said one valve member upon predetermined opening movement thereof to cause opening movement of another of said valve members.

4. A device of the character described, comprising a hollow casing having an inlet port and a plurality of outlet ports, a valve member controlling each of said outlet ports, means movable in response to fluid pressure in said casing and operatively connected to one of said valve members to cause opening movement thereof, means resisting opening movement of said one valve member by said responsive means, resilient means normally tending to open another of said valve members, and means resisting operation of said resilient means and operable by said one valve member to permit said resilient means to open said other valve member.

5. A device of the character described, comprising a hollow casing having an inlet port and a plurality of outlet ports and having a depending hollow extension with an open end, a resilient expansible-collapsible member sealing said open end and extending into said extension, means resisting movement of said member in response to fluid pressure in said casing, a valve member controlling one of said outlet ports and operatively connected to said resilient member for movement thereby, a valve member controlling another of said outlet ports, means normally acting to move said other valve member to open position, means resisting said normally acting means and co-operable with said resilient member for movement thereby to permit operation of said normally acting means.

6. A device of the character described, comprising a hollow casing having an inlet port and a plurality of outlet ports, a valve member controlling each of said outlet ports, means responsive to fluid pressure in said casing and operatively connected to one of said members, spring means normally tending to move the other of said members toward open position, means opposing operation of said spring means, means determining

the fluid pressure in said casing which will actuate said responsive means, and means operable by said responsive means upon increased fluid pressure in said casing to overcome said opposing means.

7. A device of the character described, comprising a hollow casing having an inlet port and a plurality of outlet ports, a valve member controlling each of said outlet ports, means responsive to fluid pressure in said casing and operatively connected to one of said members, spring means normally tending to move the other of said members toward open position, means opposing operation of said spring means, means determining the fluid pressure in said casing which will actuate said responsive means, means operable by said responsive means upon increased fluid pressure in said casing to overcome said opposing means, and means determining the increased fluid pressure in said casing which acting on said responsive means will operate said last-named means.

8. A device of the character described, comprising a hollow casing having an inlet port and a plurality of outlet ports, a valve member controlling each of said outlet ports, lever means in said casing engaging one of said valve members, means acting on said lever means and normally urging said one valve member to closed position, resilient means normally tending to open said one valve member, means exerting a predetermined resistance to opening movement of another of said valve members, means responsive to fluid pressure in said casing and operable to overcome said resisting means to cause opening movement of said other valve member, and means engageable with said lever means upon predetermined opening movement of said one valve member to overcome said second-named means and permit said resilient means to open said one valve member.

9. A device of the character described, comprising a hollow casing having an inlet port and a plurality of outlet ports, a valve member controlling each of said outlet ports, lever means in said casing engaging one of said valve members, means acting on said lever means and normally urging said one valve member to closed position, resilient means normally tending to open said one valve member, means operable in response to predetermined fluid pressure in said casing to cause opening movement of another of said valve members, and means operable on said lever means upon predetermined increase of pressure in said casing to permit said resilient means to open said one valve member.

10. A device of the character described, comprising a hollow casing having an inlet port and a plurality of outlet ports, a valve member controlling each of said outlet ports, lever means pivotally supported in said cas-

ing and having one end cooperable with one of said members, means urging said lever member into engagement with said one member, means tending to move said one member to open position, and abutment member carried by the other of said valve members and operable on predetermined opening movement thereof to actuate said lever means to permit said second-named means to open said other valve member, and means responsive to fluid pressure in said casing and operatively connected to said other valve member to open the same upon predetermined fluid pressure in said casing.

11. A device of the character described, comprising a hollow casing having an inlet port and a plurality of outlet ports, a valve member controlling each of said outlet ports, one of said members having abutment means, lever means cooperable with and movable by said means and having engagement with another of said valve members, resilient means acting on said lever means and normally maintaining said other valve member in closed position, resilient means tending to open said other valve member, and means responsive to fluid pressure in said casing and operatively connected to said one valve member to move said one valve member to open position and said abutment means into engagement with said lever means to permit said resilient means to open said other valve member.

12. A device of the character described, comprising a hollow casing having an inlet port and a plurality of outlet ports, a valve member controlling each of said outlet ports, one of said members having abutment means, lever means cooperable with and movable by said means and having engagement with another of said valve members, resilient means acting on said lever means and normally maintaining said other valve member in closed position, resilient means tending to open said other valve member, means responsive to fluid pressure in said casing and operatively connected to said one valve member to move said one valve member to open position and said abutment means into engagement with said lever means to permit said resilient means to open said other valve member, and means to adjust the relative positions of said abutment means and said lever means to regulate the opening of said other valve member.

13. A device of the character described, comprising a hollow casing having an inlet port, an outlet port in an end wall of said casing, an outlet port in a side wall of said casing, a lever member having a fulcrum support intermediate its ends, a valve member controlling said side outlet port and engaging one end of said member, spring means acting on the other end of said lever member and urging said valve member to closed posi-

tion, spring means tending to open said valve member, said lever member having an arm, a valve member controlling said end outlet port and having means operable to engage said arm and move said lever member upon 5 opening movement of said second-named valve member to permit said second-named spring means to open said second-named valve member, and means responsive to fluid pressure in said casing and operatively connected to said second-named valve member to open said end outlet port.

14. A device of the character described, comprising a hollow casing having an inlet port and an aperture through the wall thereof, a nipple member closing said aperture and extending into said casing and having a longitudinal bore therethrough, an annular valve seat in said bore, a reciprocable valve member cooperable with said seat and guided in 20 said bore, means exerting a predetermined resistance to opening movement of said valve member and normally maintaining said valve member seated, pressure-responsive means operatively connected to said valve member 25 and acting upon predetermined fluid pressure in said casing to overcome said resisting means and move said valve member to open position, a by-pass outlet from said casing, a valve member controlling said outlet, spring means normally tending to open said second-named valve member, resilient means opposing said spring means and normally maintaining said second-named valve member closed, and means operable upon predetermined increase of fluid pressure in said 30 casing to overcome said resilient means and permit said spring means to open said by-pass outlet valve.

35 40 In testimony whereof I have hereunto signed my name this 26th day of December, 1930.

PHILIP SHERMAN RUSSEL.
